UNITED STATES PATENT OFFICE

LOUIS G. BRINKMAN, OF DAYTON, OHIO

DESIGN FOR A ROLLER SKATE

Application filed May 28, 1930. Serial No. 35,810. Term of patent 7 years.

To all whom it may concern:

Be it known that I, LOUIS G. BRINKMAN, a citizen of the United States, residing in the city of Dayton, in the county of Montgomery and State of Ohio, have invented a new, original, and ornamental Design for a Roller Skate, of which the following is a specification, reference being had to the accompanying drawing, forming part hereof.

The figure is a perspective view of a roller skate, showing my new design.

I claim:

The ornamental design for a roller skate, as shown.

LOUIS G. BRINKMAN.
